UNITED STATES PATENT OFFICE.

THOMAS M. GUNN, OF BROOKLYN, NEW YORK.

DERRICK.

Application filed October 25, 1921. Serial No. 510,224.

To all whom it may concern:

Be it known that I, THOMAS M. GUNN, a citizen of the United States, and a resident of New York, borough of Brooklyn, in the county of Kings and State of New York, have invented certain new and useful Improvements in Derricks, of which the following is a specification.

This invention relates to derricks and particularly to devices of that character which are mounted on boats or barges. The object of my improvements is to provide a derrick suitable for use on barges, which may be erected on the deck and near a lateral edge thereof, and which may be folded down onto the barge when not in use, to permit the barge to pass under bridges and the like. A further object of my improvements is to provide a folding derrick which may be erected and folded down by one man. Other objects will appear later herein.

My improvements are illustrated in their preferred embodiment in the drawings accompanying this specification, wherein:—

Figure 1 is an end elevation of a barge on which my improved derrick is erected. Fig. 2 is a side elevation of the upper portion of the barge on which said derrick is shown, in full lines in folded position and in dotted lines in erected position. Fig. 3 is a plan view corresponding with the elevation of Fig. 2. Fig. 4 is a detail sectional elevation on line 4—4 of Fig. 2, showing the mast support. Fig. 5 is a fragmentary sectional side view on line 5—5 of Fig. 4. Fig. 6 is a sectional plan view on line 6—6 of Fig. 1. Figs. 1, 2 and 3 are to one scale. Figs. 4, 5 and 6 are to another scale, and which scale is about four times that of Figs.

1, 2 and 3.

My improved derrick includes a mast 2 pivotally mounted on pin 3 near its foot to rotate on a horizontal axis, between ears 5, 5 of step 7, mounted for rotation on a tubular member 8 having a vertical axis in bearing 9 of deck-block 22. Said horizontal axis pin 3 is preferably offset to one side of vertical axis sleeve 8, so that mast 2 is entirely at one side of said vertical axis, for permitting hoist rope 23 in its vertical run to lie in the axis of rotation of mast 2. At the top of said mast, pivot plate 10 may be similarly offset from said mast so as to present its pivotal portion 11 in line with the axis of tubular member 8 of step 7. Mast 2 is thereby mounted in parallelism with its

axis of rotation but eccentric thereto. Directly across the barge B, on side deck 12 thereof, is deck-block 14 similar to block 22 on side deck 13. On block 14 is fixed ear 15, to which is pivoted on horizontal stud 17, the lower end of back-leg 16. The axis of stud 17 lies transverse the barge. The upper end of said back-leg 16 engages vertical pivot 11 fixed to the top of mast 2. Said mast being mounted for rotation about a vertical axis, Fig. 1, and eccentric thereto, when turned to present its axial pin 3 at the foot thereof crosswise the barge, said mast and back-leg may be folded down onto the deck of the barge.

Said mast is provided with the usual boom 18 pivotally mounted at its lower end between ears, as 19, of vertically adjustable block 20, slidably mounted in guideway 21 of mast 2. Said block may be locked in any given adjusted position by lock-pin 42 thrust therethrough and into one of a number of suitable holes, as 24, in said mast, Fig. 6. Boom 18 may have its upper end 80 adjustably supported from mast 2 by well known means such as tackle 25, the free end of the rope thereof being secured to cleat 26 on mast 2. Said boom is provided with the usual hoisting means 27, the hoisting rope 85 thereof being preferably passed through an opening in the upper part of mast 2 and over sheave 28 pivoted in said opening. Said sheave is of suitable diameter and location transverse said mast, Fig. 1, to permit the vertical run of hoist rope 23 to coincide with the axis of rotation of mast 2. Said rope passes downwardly through tubular base 8 of step 7, then about sheave 29 pivoted in lower portion 22^a of 95 deck-block 22, and thence horizontally to drum 31 of hoisting engine 30, fixed to the deck at some distance from mast 2, as shown in Figs. 2 and 3. Deck blocks 14 and 22 may be removably secured to the deck so as 100 to permit the erection or removal of my improved derrick without injury to the barge. Secured to said deck is an ear 32, Figs. 1 and 5, for each of said blocks. Pivotally connected thereto by bolt 33 is reversed U shaped member 34, with the top of which vertical bolt 35 is in threaded engagement. Nut 36 on the top of said bolt is efficient for holding the deck block, as 22, securely to the deck.

Some suitable removable means such as opposite guy lines 37, 38 may be employed

for holding mast 2 and back leg 16 erected, as in Fig. 1, and in the dotted position of Fig. 2. For lowering my improved derrick, one of said guy lines, as 38, having been 5 freed from its fastening on the deck, may be attached to tackle 39 operably connected with a drum 40, as of engine 30. As mast 2 is lowered said guy line 38 is passed over sheave 41 of strut 43 thereby providing a 10 purchase for the final portion of the lowering operation onto deck 13. The operation of raising the derrick is the opposite of that just described for lowering. Strut 43 may be removed and stowed when not in use.

15 I claim:

1. In a device of the character described the combination of a step mounted for rotation on a vertical axis, a mast having its 20 foot pivotally mounted on a horizontal axis in said step, said mast having a pivot at its top, a back leg having its upper end in pivotal engagement with said mast top pivot and its lower end pivotally mounted on a horizontal axis remote from said step, and means for supporting said mast and 25 back leg in erected positions respectively.

2. In a device of the character described the combination of a step mounted for rotation on a vertical axis, a mast having its 30 foot pivotally mounted on a horizontal axis in said step, said mast having a pivot at its top, a back leg having its upper end in pivotal engagement with said mast top pivot and its lower end pivotally mounted 35 on a horizontal axis remote from said step, opposite guy lines for supporting said mast and back leg in erected positions respectively, and means for erecting and lowering said mast and back leg.

40 3. In a device of the character described the combination of a step mounted for rotation on a vertical axis, a mast having its foot pivotally mounted on a horizontal axis in said step, said horizontal axis being offset from said vertical axis, said mast having a pivot at its top in line with the vertical axis of said step, a back leg having its upper end in pivotal engagement with said mast top pivot and its lower end pivotally mounted 45 on a horizontal axis remote from said step, means for supporting said mast and back leg in erected positions respectively, and means for slackening said supporting 50 means for lowering said mast and back leg.

4. In a device of the character described the combination of a step mounted for rotation on a vertical axis, an axial hole through said step, a mast having its foot 60 pivotally mounted on a horizontal axis in said step, said horizontal axis being offset from said vertical axis, said mast having a pivot at its top in line with the vertical axis of said step, a back leg having its upper end in pivotal engagement with said mast 65

top pivot and its lower end pivotally mounted on a horizontal axis remote from said step, and a sheave pivotally mounted in and near the top of said mast, said mast being offset from its upper pivot and from said step axis sufficiently to permit a rope passing over said sheave to enter the axial hole in said step free of said mast.

5. In a device of the character described the combination of a step mounted for rotation on a vertical axis, an axial hole through said step, a deck-block in which said step is pivotally mounted, a mast having its foot pivotally mounted on a horizontal axis in said step, said horizontal axis being offset from said vertical axis, said mast having a pivot at its top in line with the vertical axis of said step, a back leg having its upper end in pivotal engagement with said mast top pivot and its lower end 70 pivotally mounted on a horizontal axis remote from said step, a sheave pivotally mounted in and near the top of said mast, said mast being offset from its upper pivot and from said step axis sufficiently to permit a rope passing over said sheave to enter the axial hole in said step free of said mast, and a sheave pivotally mounted on a horizontal axis in said deck-block below said step and having its rope-engaging periphery in line with the axis of said step.

6. In a device of the character described the combination of a step mounted for rotation on a vertical axis, an axial hole through said step, a deck-block in which said step is pivotally mounted, a mast having its foot pivotally mounted on a horizontal axis in said step, said horizontal axis being offset from said vertical axis, said mast having a pivot at its top in line with the vertical axis of said step, a back leg having its upper end in pivotal engagement with said mast top pivot and its lower end 100 pivotally mounted on a horizontal axis remote from said step, a boom having its lower end mounted on said mast, a sheave pivotally mounted in and near the top of said mast, said mast being offset from its upper pivot and from said step axis sufficiently to permit a rope passing over said sheave to enter the axial hole in said step free of said mast, means for supporting said mast and back leg in erected positions respectively, a sheave pivotally mounted on a horizontal axis in said deck-block below said 110 step and having its rope-engaging periphery in line with the axis of said step, and a rope from said boom passing over said sheave near the top of said mast, through said axial hole in said step and under the 115 sheave in said deck-block.

7. In a device of the character described the combination of a step mounted for rotation on a vertical axis, an axial hole through said step, a deck-block in which said step is 120

5 pivotally mounted, a mast having its foot pivotally mounted on a horizontal axis in said step, said horizontal axis being offset from said vertical axis, said mast having a
 10 pivot at its top in line with the vertical axis of said step, a back leg having its upper end in pivotal engagement with said mast top pivot and its lower end pivotally mounted on a horizontal axis remote from said step, a boom having its lower end adjustably mounted on said mast, a sheave pivotally mounted in and near the top of said mast, said mast being offset from its upper pivot and from said step axis sufficiently to permit a rope passing over said sheave to enter the axial hole in said step free of said mast, opposite guy lines for supporting said mast and back leg in erected position and removably connected for erecting and lowering
 20 said mast and back leg, a sheave pivotally mounted on a horizontal axis in said deck-block below said step and having its rope-engaging periphery in line with the axis of said step, and a rope from said boom passing over said sheave near the top of said mast through said axial hole in said step and under the sheave in said deck-block.

8. In a device of the character described the combination of a step mounted for rotation on a vertical axis, an axial hole through said step, a deck-block in which said step is pivotally mounted, a mast having its foot

35 pivotally mounted on a horizontal axis in said step, said horizontal axis being offset from said vertical axis, and a sheave pivotally mounted on a horizontal axis in said deck-block below said step and having its rope-engaging periphery in line with the axis of said step.

9. In a device of the character described 40 the combination of a step mounted for rotation on a vertical axis, an axial hole through said step, a deck-block in which said step is pivotally mounted, a mast having its foot pivotally mounted on a horizontal axis in 45 said step, said horizontal axis being offset from said vertical axis, a boom having its lower end mounted on said mast, a sheave pivotally mounted in and near the top of said mast, said mast being offset from its upper pivot and from said step axis sufficiently to permit a rope passing over said sheave to enter the axial hole in said step free of said mast, a sheave pivotally mounted on a horizontal axis in said deck-block 50 below said step and having its rope-engaging periphery in line with the axis of said step, and a rope from said boom passing over said sheave near the top of said mast through said axial hole in said step and under the sheave 55 in said deck-block.

In witness whereof, I hereby affix my signature this 24 day of October, 1921.

THOMAS M. GUNN.
